UNITED STATES PATENT OFFICE.

JOHN C. G. BONNEY, OF BROOKLYN, NEW YORK.

WINDOW-WASHING APPARATUS.

Application filed April 5, 1921. Serial No. 458,822.

To all whom it may concern:

Be it known that I, JOHN C. G. BONNEY, a citizen of the United States, residing in the borough of Brooklyn, county of Kings, and 5 State of New York, have invented a new and useful Improvement in Window-Washing Apparatus, of which the following is a description.

This invention relates to devices for washing window panes, and particularly has reference to a manually operated device adapted for simultaneously washing both the inside and outside of the window pane without reaching out of the window or leaning 15 over the window sill.

Among the objects of my invention may be noted the following: to provide a manually operated device which can be utilized for simultaneously washing both sides of the 20 window pane; to provide a window washing device which can be quickly and easily manipulated and which is safe to the operative, since the latter does not have to lean out of the window or sit on the window sill; to provide 25 a window washing device which is manually operated and which will either wash or dry both the inside and the outside of the window pane at the same time, thus facilitating the washing and drying operations, and, 30 since both sides of the pane are operated on at one time, the operator is able to see and remove all spots, smears and dirt, regardless of whether they are on the inside or the outside of the window pane; to provide a window 35 washing device which is effective, simple, and can be handled with great facility so as to wash the window panes on both sides safely and rapidly; to provide a window washing device which is economical to produce, durable and capable of being quickly 40 adjusted to the window sashes for the purposes stated in the foregoing.

With the above objects in view and others which will be detailed during the course of 45 this description, my invention consists in the parts, features, elements and combinations thereof hereinafter described and claimed.

In order that my invention may be clearly 50 understood, I have provided drawings wherein:

Figure 1 is a perspective view of a portion of a window frame and sash, showing my invention in operative position;

Figure 2 is a top plan view of the form of 55 my invention shown in Figure 1, a part being broken away;

Figure 3 is a side view of Figure 2, a portion of a window pane being shown in place; 60

Figure 4 is a plan view of another form of my invention, a part being broken away;

Figure 5 is a side view of Figure 4, a portion of a window pane being shown in place;

Figure 6 is a plan view of a third form of 65 my invention;

Figure 7 is a plan view showing a fourth form of my invention;

Figure 8 is a side view of Figure 7;

Figure 9 is a sectional side view of a fifth 70 form of my invention; and

Figure 10 is a sectional view substantially on the line 10—10 of Figure 9.

My invention, embodied in a simple form of apparatus, is shown, for example, in Figures 1, 2 and 3 and, therein, a rectangular block 1 is provided having opposite sides 2 inclined or converging toward each other. The inner edge of the block is provided with a recess 3 in which is mounted an anti-frictional roll 4, held in position by a screw-bolt 5 passing through the block 1 from top to bottom and spanning the recess 3, which bolt, in addition to supporting the anti-frictional roll 4, and affording a journal therefor, has the function of imposing tension, as presently described. Applied to the block 1, on the opposite inclined sides 2 thereof are a pair of resilient bars 6, the inclination of the surfaces 2 of the block causing the 80 said bars to normally tend to converge toward each other so that, at their free ends, they would be very nearly in contact. The block and bars may be made of any suitable material, preferably wood, although light 85 metal may be found suitable and serviceable for some of the parts.

The free ends of the converging bars 6 are each provided with a rectangular pad holder 7, one of which, the outside one, is 100 of slightly greater width than the other one, this being for the purpose of enabling the outside pad to reach into all the corners and to the extremes of the window pane, and also for the purpose of compensating for 105 the drag imposed upon the outside pad which may result in lateral flexure of the outside bar of the device, the drag being im-

posed by the friction of the pad upon the window pane, and the fact that the outside bar is compelled to follow the inside bar without positive pressure being applied directly thereto. The pad holders are rigidly secured in the ends of the bars 6 by screws 8 passing through the said bars and into the extension 9 of the holders. The shape of the pad holders 7 is preferably rectangular 10 in order that, when in operation, the angles thereof may reach into and clean and polish the angles or corners of the window panes. The pad holders 7 are preferably made of light wood; but, they may be stamped out 15 of metal and formed of one or more pieces. In either instance, it may be desirable to cover the pad holders with rubber 10, see Figure 9, in order to preserve the wood and prevent it from warping, in the one instance, and prevent the metal from rusting, 20 in the other instance. The pad holders 7 are covered with cloth caps or pads 11 made of any suitable material and of any desired thickness, and formed in any manner found 25 efficacious and economical. Whatever may be the material or form of the pads, when applied to the holders 7, they will take the form of the latter substantially as shown in Figures 1 to 3. The caps or pads may be 30 made of elastic material which normally will contract upon the holders when applied thereto, so as to cling thereto during operation. If the material of the caps or pads is not normally elastic, they may be provided 35 with a tie-cord or other equivalent means for retaining the same on the holders. Or, as shown in Figures 4 and 5, the outer surfaces of the holders may be provided with 40 spring clamps, the same being adapted to engage and press upon the edges of the caps or pads placed on the holders. The said clamps may consist of a base 12 rigidly secured to the holder, having a jaw 13 hinged thereto, controlled by a coiled spring 14, this 45 being a simple form of clamp readily applied to the outside of the blocks for the purpose of holding the caps or pads in position. Four clamps may be provided on each holder.

50 At its pad end, the apparatus is preferably provided with a handle 15, the same being secured in any suitable manner to one of the bars 6 and arched sufficiently, as shown in Figures 1 and 3, to enable the operator to readily grasp the same and manipulate the apparatus.

55 As previously stated, the bars 6 are normally elastic or resilient and, by reason of the manner in which they are mounted, converge toward each other almost to contact at their free ends. When the pad holders are 60 mounted therein, however, the bars are flexed away from each other, giving them the curved form shown in Figures 3 and 5, 65 which imposes tension upon the holders and pads and causes the latter, when operating upon the window panes, to forcibly press against the opposite sides of the window pane so as to produce sufficient friction to either clean, or dry and polish, the panes simultaneously on both sides. When the caps or pads are applied to the holders, the arms are sprung apart, as will be readily understood, the application of the pads being accomplished quickly and with facility. 70 When the windows have been washed on both sides by the use of wet pads, the latter can be quickly removed and dry pads substituted therefor. As many wet pads can be used as desired, and likewise as many drying or polishing pads as may be found necessary. Instead of removing the pads and substituting others, the pad holders themselves may be removable, so that, after using wet pads, other pad holders 75 with dry pads thereon can be quickly substituted for the holders having the wet pads thereon. In order to avoid scratching the window sash, or wearing the paint or varnish therefrom, and also to avoid wear upon 80 the bars 6, soft pads of felt, for example, can be applied to the inner surfaces of the bars 6, as indicated at 6^a, Figure 5. Thus the window sash is preserved and wear upon the bars 6, which might tend to weaken 85 them, is prevented. The anti-frictional roll 4, mounted in the crotch of the device, is adapted to travel on the upper and lower edges of the sash during the process of 90 washing the window, as shown in Figure 1, 100 said roller avoiding friction, binding, etc., and facilitating the travel of the apparatus during operation.

95 The block 1, at its outer end, has secured thereto a plate 16, to the opposite edges of 105 which a tension bar 17 is hinged, as at 18, the same extending along the outer surface of each of the bars 6. At its inner end, each of the tension bars 17 is provided with a transversely extended, enlarged portion or 110 bar 19, projecting inwardly from the inner surface of the tension bar and adapted to press on the outer surface of the bar 6. The screw-bolt 5 passes through the two tension bars, its head 20 pressing on one tension bar and the knurled nut 21 pressing upon the other, and, by turning the nut, is adapted to cause the tension bars to bear with more or less of pressure upon the bars 6, thus increasing as desired the normal tension of said bars and the tension imposed by 115 them and the pads upon the window pane being cleaned.

120 In the form of my invention shown in Figures 4 and 5, the pad holders are removable and may be secured in place in the ends of the bars 6 by means of a pin 22 carried by a spring 23 secured to the outer surface of the bar adjacent the aperture therein, the pin 22 entering an aperture in the side of 130

the angular teat or lug 24 of the pad holders, which teat passes through an aperture in the arm 6.

Instead of the spring pin shown, the pad holders may be removably held by a cotter-pin 25 passing through the angular teat 24 of the pad holders, as shown in Figure 6, a chain or similar device 25^a being employed to hold the cotter-pin and prevent it from being 10 dropped and lost, the chain being secured by means of an eye-screw 25^x to the bar 6.

Still another way of making the pad holders removable is shown in Figures 9 and 10, wherein the blocks are also shown as 15 stamped out of sheet metal. In this form of my invention, the holders are composed of a flat, flanged member 26, to which is secured a cymbal shaped member 27, the circumference of which is held in place by 20 overturning the flange of the member 26. The member 27 is provided with a hollow teat or extension 28, which passes through the aperture in each of the bars 6 and is removably held in place by spring detents 25 consisting of a hollow, rectangular boxing 29 secured within the teat 28 by soldering. The boxing 29 holds a coiled expansion spring 30, the opposite ends of which press against 30 detents 31 having rounded end surfaces 32, and held in place by flanges 33 at the open ends of teats 28 to prevent them from falling out of the boxing 29. Pressure upon the detents 31, when the teats are slipped into place, will cause the detents to recede. They 35 will automatically spring into holding position shown in Figure 9. To remove the pad holders, pressure is applied to the rounded ends 32 of the detents 31, either simultaneously or one at a time, and the teats 40 28 can then be slipped out of position shown in Figure 9, and the pad holders removed by pressure upon the same, the detents yielding until the teats are sufficiently withdrawn.

In the form of my invention shown in 45 Figures 7 and 8, the pad holders 34 are shown in flat form, rectangular in shape, and of molded, pressed or shaped material, and may be made of any composition found suitable for the purpose. Each of the pad 50 holders 34 is provided with a member 35 having its upper surface rounded so as to permit the holder to rock lengthwise of the bars 6, but not transversely. The members 35 are secured to the holders 34 by means of 55 a plurality of screws 36, for example, thus rigidly securing the two parts together. The members 35 are provided on opposite sides with lugs or ears 37 which may be secured in place by screws 38, and which extend 60 through apertures provided for them in the arms 6. A spring holder 39 is provided with oppositely extending arms 40 passing through apertures in the upper ends of the lugs or ears 37, thus loosely and removably 65 securing the pad holders to the arms 6.

Pressure on the branched legs of the holders 39 will remove the arms 40 from the ears 37, enabling the holders 34 to be removed. Thus the pad holders 34, by reason of the form of the members 35, can rock lengthwise of the bars 6, but cannot rock or tilt laterally of the latter. In order to prevent the loss of the holders 39, they may be loosely secured to the end of the bar 6 by means of a staple 39^a driven into the bar and 70 through the eye of the holder.

In each form of my device a handle 15 is provided, and in each form pads may be applied to the holders with facility, either by stretching them on or by clamping on, 80 as shown in Figures 4 and 5. In all the forms of my invention, excepting that shown in Figures 1, 2 and 3, the pad holders are removable and may be quickly removed and applied, whenever found desirable, 85 either for substitution of a holder with a dry pad or a holder with a wet pad, or for removing the pads from the holders. The tension on the pane of glass or surface being cleaned, dried or polished can be increased or decreased by manipulating the nut 21; and the entire apparatus is readily and easily manipulated by grasping the handle 15. The anti-frictional roll 4 will prevent the apparatus from dragging on 90 the top or bottom bars of the sash; and the latter may be raised and lowered to any extent desired during operation. Wet pads, dry pads and polishing pads can be quickly substituted the one for the other as occasion 95 demands, or sets of holders with the pads applied can be supplied with an apparatus so that one or the other can be quickly substituted.

From the foregoing it will be seen that I 105 have provided a simple, compact, durable apparatus which is economical to produce and by means of which window panes and other suspended surfaces can be cleaned, washed, scoured of polished simultaneously 110 on both sides and quickly and with facility. The length of the apparatus will be such as to reach beyond the middle of the surface which is to be operated upon, so that the lower half can be scoured or polished 115 and then the upper half by simply reversing the position of the apparatus shown in Figure 1; and the apparatus will be made of different sizes, so as to operate in connection with different sizes of window panes or other surfaces to be scoured, cleaned or 120 polished. The antifrictional roll runs with great facility along the edge of the window sash, either top or bottom, according to which part of the window pane is being 125 operated upon.

Having thus described my invention, what I claim and desire to secure by Letters Patent is:

1. In a window cleaning device, a sup- 130

porting block the opposite sides of which are inclined so as to converge toward each other, resilient arms secured at their inner end to the inclined sides of said block so that their free ends converge toward each other, pad-holders secured to the free ends of the arms, and means applied to the arms for increasing the tension of the arms so as to increase the pressure of the pads upon the window-panes.

2. In a window cleaning device, a supporting block, resilient arms secured at one end to the block and at their free end provided with an aperture, pad-holders each provided with a lug for passing through the aperture in the free end of the arm, and resilient means for detachably holding the pad to the arm.

3. A device such as set forth in claim 2, wherein the pad-holders are of different dimensions, for the purpose set forth.

4. In a window cleaning device, a supporting block, resilient arms secured at one end to said block and having their opposite end free, pad-holders for said free end each

having its back rounded so that it may rock relatively to the arm, and means for detachably securing the pad-holders to the arms.

5. In a window cleaning device, a supporting block, resilient arms secured at one end to said block and having their opposite end free, pad-holders secured to the free end of each arm, and means for applying tension to the arms including tension bars hinged at opposite sides of the block and extending along and bearing upon the arms, and a screw-bolt passing through the arms and block and having means for regulating the tension on the bars.

6. In a window cleaning device, a supporting block, resilient arms secured at one end to the block and at their free end provided with pad holders, pads carried by the holders, means causing the arms to normally force the pads toward each other, and pads applied to the inner surface of the arms between the supporting block and pad holders.

JOHN C. G. BONNEY.
